UNITED STATES PATENT OFFICE.

FRANKLIN O. ANDREWS AND FRANK W. TRENN, OF WILLOUGHBY, OHIO, ASSIGNORS
TO THE ECONOMY ENGINEERING COMPANY, OF WILLOUGHBY, OHIO, A CORPOR-
ATION OF OHIO.

TAPPING MACHINE.

Application filed August 5, 1922. Serial No. 579,952.

To all whom it may concern:

Be it known that we, FRANKLIN O. ANDREWS and FRANK W. TRENN, both citizens of the United States, residing at Willoughby, in the State of Ohio, have invented certain new and useful Improvements in Tapping Machines, of which the following is a specification.

The invention relates particularly to machines for providing threads on the interior bores of nuts or other blanks.

In the accompanying drawings is shown one specific structure embodying the invention. Figure 1 is a front elevation of the machine. Fig. 2 is a transverse vertical section. Fig. 3 is a plan view of a fragment of the mechanism for feeding nuts to the tapper. Fig. 4 is a side elevation of a portion of the apparatus for feeding nuts to the tapper. Fig. 5 is a transverse vertical section of a portion of the apparatus for reciprocating the tapper. Fig. 6 is a longitudinal section of the structure shown in Fig. 5 taken on the line 6—6 and Fig. 7 is a detail elevation.

There is a main drive shaft 1 on which beveled gears 2 drive the spindle 3 through intermediate gears 4. The spindles 3 are provided at their lower ends with chucks 5 which hold taps 6 which cut internal threads in the nut blanks 7. Towards the upper ends of the spindles 3 are discs 8 on which rest springs 9 which in turn support weight blocks 10 loose on the spindle. Above these are bearing blocks 11 whose positions may be adjusted by a lock nut 12. Yokes 13 engage the bearing blocks 11 to raise the spindles, the yokes themselves being pivoted on a transverse rod 14 at the rear of the machine. The yokes fall when the weights 10 cause the spindles to fall. In the yokes 13 are bearing rollers 15 which are engaged by cams 16 loosely mounted about a transverse cam shaft 17. The shaft 17 is driven by a belt 18 from the main shaft 1. On the shaft 17 and within the cams 16 are toothed discs 19 which are adapted to be engaged by spring supported latches 20 and 21 carried by the cams 16 so that

the cams 16 may be rotated to raise and lower the spindles 3. The latches 20 and 21 carry pins 22 which are engaged by cam slots 23 in rings 24 loosely mounted on the cams 16. Pins 25 extending from these rings 24 may be engaged by forks 26 piv-

oted at 27 at the rear of the machine. The forks 26 are provided at their lower arms with hooks 27^a. The forks 26 are normally held in position for the hooks 27^a to engage the pins 25. This is effected by vertical rods 28 having thimbles 29 at their tops on which the forks 26 normally rest. In this position the upper arms 30 of the forks 26 are out of the path of the pins 25. The rods 28 are supported by toggles 31 which are operated by transverse rods 32. When the rods 32 are pulled out as allowed by the stops 33 the toggles 31 are substantially straight and the forks are supported so that the hooks 27^a may engage the pins 25. When the rods 32 are pushed inward the toggles 31 collapse and allow the forks 26 to drop so that their upper ends 30 may engage the pins 25. The thimbles 29 are supported on springs 49 so that when the yokes 13 come down bolts 34 carried by the yokes strike the forks 26 and depress them sufficiently to force the hooks 27^a downward from the path of the pins 25. When the yokes 13 rise the springs 49 lift the hooks 27^a into the path of the pins 25.

Carried by the yokes 13 are rearwardly and downwardly extending curved rods 35 at the lower ends of which are adjustable blocks 37. Through the blocks 37 pass second vertical rods 38 provided with adjustable stops 39 and 40 above and below the blocks 37. The rods 38 at their lower ends are provided with arms 41 near the rear ends of shafts 42 extending from rear to front of the machine. At their front ends the shafts 42 carry depending arms 43 to which are pivoted blank pushers 44. The arrangement is such that the upward and downward movement of the yokes 13 moving with the spindles 3 reciprocate the blank pushers 44. Chutes 45 bring blanks into position to be engaged by the reciprocating blank pushers 44 which feed the blanks one at a time into seats directly under the taps. Adjustable positioning blocks 46 and 47 are provided to insure blanks being properly placed to be threaded by the taps.

It will be understood that the spindles all operate continuously but, as indicated in Fig. 1, they need not be all in the same position. The operation will be described for a single spindle. When the machine is started the spindle will be rotated and since

there is no blank in position under it to be acted upon it will fall immediately to its lowermost position carrying with it the yoke 13. This will cause the bolt 34 to strike the 5 fork 26 and so depress it against the spring 49 and so free the pin 25 from the hook 27^a. This will allow the latches 20 and 21 to advance and engage the toothed disc 18 which is rotating with the cam shaft 17 10 (which turns counter clockwise in Fig. 2). This will cause the cam 16 to raise the spindle 3. The upward movement of the yoke 13 thus caused will actuate the blank pusher 44 to force a blank into position to be 15 operated on by the spindle. Further movement of the cam 16 will allow the weight 10 to force the rotating spindle down to operate on the blank. In the meantime the pin 25 has proceeded to the lowermost point 20 and been engaged by the hook 27^a which has been lifted under the influence of the spring 49. This causes the pins 22 to ride on the cams 23 so as to disengage the cam 16 from the cam shaft. The engagement of 25 the tap with the blank keeps the spindle from falling far enough to depress the fork 26. The latches 20 and 21 are oppositely disposed so that one latch may prevent any backlash of the cam 16 which is actuated by 30 the other latch. The spindle can now proceed to operate the tap to properly thread the blank without interference from the cam 16. When the tap goes entirely through the blank the spindle drops sud- 35 denly causing a hammer blow of the bolt 34 on the yoke 26 to repeat the operation. Blanks thus finished are assembled on the spindle shank and eventually so many blanks are assembled that the spindle will 40 not fall far enough to allow the yoke to operate the clutch mechanism. It is now necessary for the operator to attend the machine. By pushing in on the rod 32 the toggle 31 collapses and lowers the thimble 45 29 a sufficient distance to disengage the pin 25 from the hook 27^a and to hold the upper end 30 of the fork in position to engage the pin 25 at the uppermost point in its travel. At this time the cam 16 will be in

position to hold the spindle 3 in its uppermost position. The engagement of the pin 25 with the upper arm 30 causes the spindle to remain in its uppermost position in which the tap may be loosened from the spindle and the finished blanks removed. The tap 55 may then be returned to the spindle and the rod 32 pulled forward releasing the pin 25 from the arm 30 and allowing the operation to proceed as before.

We claim as our invention:

1. A spindle, an arm moving with the spindle, a rotary shaft, a cam on the shaft and engaging the arm, a clutch between the cam and shaft, and means on the arm controlling the clutch.

2. A spindle, an arm moving with the spindle, a rotary shaft, a cam on the shaft and engaging the arm, a clutch between the cam and shaft, means on the arm controlling the clutch, and means controlled by the 70 arm to move a blank into operative position for the spindle.

3. In a machine for tapping nuts, the combination of a spindle, an arm moving with said spindle, a rotary shaft, a cam on said shaft and adapted to engage said arm to raise said spindle, a clutch between said cam and shaft, resilient means normally holding said clutch in its disengaged position, and means on said arm for throwing said clutch 80 into engaging position upon a predetermined downward movement of said spindle.

4. In a machine for tapping nuts, the combination of a spindle, an arm moving with said spindle, a rotary shaft, a cam on said shaft and adapted to engage said arm to raise said spindle, a clutch between said cam and shaft, resilient means normally holding said clutch in its disengaged position, means on said arm for throwing said 90 clutch into engaging position upon a predetermined downward movement of said spindle, and means controlled by said arm to move a blank into operative position for said spindle.

FRANKLIN O. ANDREWS.
FRANK W. TRENN.
